CONTROLLING MECHANISM FOR INTERNAL-COMBUSTION ENGINES.

1,343,980.

Specification of Letters Patent. Patented June 22, 1920.

Application filed March 3, 1917, Serial No. 152,296. Renewed October 31, 1919. Serial No. 334,821.

To all whom it may concern:

Be it known that I, CHARLES A. MULLER, a citizen of Switzerland, and resident of Islip, county of Suffolk, city and State of New York, have invented certain new and useful Improvements in Controlling Mechanisms for Internal-Combustion Engines, of which the following is a specification.

My invention relates to controlling mechanism for internal combustion engines and more particularly to that type thereof commonly known as oil engines in which the initial motive power at the starting of the engine in many forms of this engine is compressed air. In such engines after a sufficient momentum has been obtained under the influence of said compressed air the supply of the latter to the combustion chamber of the engine is cut off and the usual explosive mixture consisting of oil and air is substituted as a motive force, it being understood that in some cases the introduction of the oil may commence before the compressed air has been finally cut off. My improvement has for its object the provision of a simple mechanism whereby such engines may at all times be efficiently controlled and more particularly contemplates an improved and simplified arrangement whereby said engines may be quickly and positively reversed when necessary or desired. Other objects of my invention will appear from the description hereinafter and the features of novelty will be pointed out in the appended claims.

In the accompanying drawings I have diagrammatically shown an example of my invention for the purpose of illustration and description. In said drawings Figure 1 is a diagrammatic view showing an engine cylinder and its cooperating parts in operative combination with my improvement; Fig. 2 is a view of the operating dial with reference to which my controller is operated; Fig. 3 is a view, part section and part elevation, on an enlarged scale showing the details of construction of my improved control valve and of the mechanism by which it is operated; Fig. 4 is a section along the line 4—4 of Fig. 3; and Fig. 5 is an elevation, of diagrammatic character, showing the application of my invention to a three cylinder engine.

As shown in the drawings 5 represents the cylinder of an engine in which the custom-

ary piston 6 reciprocates, the latter being connected in the well known way with one end of a piston rod 7, the other end of which is operatively connected with the crank 8 forming part of or connected with the main driving shaft 9 mounted in suitable bearings. The cylinder 5 is provided with the usual exhaust 10 and an inlet 10^a while an ignition device of any suitable type such as for instance an igniter tube 11 is located in the combustion chamber in the well known manner. The engine may in addition comprise any suitable construction, while the shaft 9 may be operatively connected with any desired or known mechanism to impart motion thereto as will be readily understood.

As shown diagrammatically the combustion chamber 5^a of the cylinder 5 is connected by means of a pipe 12 with an annular chamber 13 forming part of a valve cylinder 14 and communicating with the interior thereof through an annular slot 15, the cylinder 14 in turn being connected by means of a pipe 16 with a source of compressed air.

The communication between the interior of the valve cylinder 14 and the annular chamber 13 and consequently the communication between the pipes 12 and 16 is controlled by means of a suitable valve 17 slidably mounted in said cylinder 14.

As shown in the illustrated example the valve 17 is provided with annular flanges 18 forming an intermediate annular space 19 and is further constructed with one or more channels 20 extending through said valve in an axial direction. The said channels 20 establish communication between those parts of the cylinder 14 located upon opposite sides of said valve whereby equalization of pressure and perfect balance is secured. The valve 17 in the illustration is carried by a hollow stem or sleeve 21 slidably mounted upon a tubular rod 22 depending from the upper portion of the valve cylinder 14 and communicating with the atmosphere through the outlets 23 formed in said valve cylinder. The tubular rod 22 is provided with a plurality of slots 24 so located as to be intersected by the plane of the annular slot 15 of the cylinder 14, the hollow stem 21 being formed with similar slots 25 adapted to register with said slots 24 as the valve is actuated. The valve 17 itself is

provided with a plurality of radially extending passages 26 corresponding in number to the slots 25 and establishing communication between said slots 25 and the annular space 19 for the purpose to be more fully described hereinafter. The valve stem 21 extends exteriorly beyond the one end of the cylinder 14 through a suitable stuffing box or the like 27, it being understood that in some cases, the stem 21 or its equivalent may also extend through the opposite end of said cylinder for guiding purposes instead of being arranged as in the illustration. The valve stem 21, at its outer end, is rigidly and preferably detachably, connected with a cross-head 28, the latter being pivotally connected at 29 with one end of a link 30, the other end of which is pivotally connected at 31 with a second link 32. The latter in turn is pivotally connected at 33 with an arm 34 rigidly secured either directly to a toothed segment 35 or to a shaft 36 upon which said segment 35 in such case is also rigidly mounted, it being understood that in either case the point 36 represents a pivot journaled in suitable stationary bearings. The segment 35 is in mesh with a pinion 37 carried by a rod 38 rotatably mounted in suitable stationary bearings and provided at one end with an actuating means which as shown may consist of a crank 39 provided with a pointer 40 at its free end. The said actuating means of whatever nature it may be is preferably located in close proximity to the one face of a stationary indicating plate 41 suitably supported and provided upon said face with suitable designations 42, 42^a, 42^b, 42^c and 42^d located in coöperative relation to said pointer 40, a stop 43 being provided upon said plate 41 to arrest the movement of the crank 39 as will be more fully described hereinafter.

In addition to the above, a third link 44 has its one end pivotally connected at 31 with the links 30 and 32 and its other end operatively secured for instance to a crank 45 forming part of or secured upon a counter shaft 46 journaled in suitable stationary bearings. The counter shaft 46 is operatively connected with the main shaft 9 in any suitable manner so as to operate in harmony therewith or at the same speed and as shown carries a bevel pinion 47 in mesh with a bevel pinion 48 mounted upon an auxiliary shaft 49. The latter is journaled in suitable stationary bearings and in the diagrammatic illustration is provided with a gear 50 which meshes with a gear 51 secured upon the main shaft 9 to rotate therewith. The connection between the combustion chamber 5^a of the cylinder 5 and the pipe 10 is controlled by means of a valve 52 which is positively operated in a direction to open it in any suitable manner and as shown is carried by a stem 53 which is

slidably mounted in suitable stationary bearings and is controlled and operated for instance by means of a cam 54 rigidly mounted upon the rod 38; a spring 52^a or any other suitable means may be provided for closing 70 said valve at the proper time.

The combustion chamber 5^a of the cylinder 5 is further connected by means of a pipe 55 with a source of oil or other suitable fuel and suitable means may be provided in said 75 combustion chamber 5^a whereby the fuel or oil which is injected into the latter from the pipe 55 is atomized or scattered throughout said combustion chamber to form an explosive mixture. The injection of the fuel 80 into the combustion chamber 5^a may for instance be accomplished by means of a fuel pump 56 located at a convenient point in the pipe 55 and controlled and operated in any suitable manner as by being operatively 85 connected with an eccentric 57 located upon the main shaft 9. In addition to this the arrangement includes a by-pass 58 connected at its opposite ends with the pipe 55 and forming therewith a by-pass circuit at some 90 point between the source of fuel supply and the cylinder 5. The by-pass 58 may be controlled in any suitable manner as by means of a slide valve 59 carried by a stem 60 provided at its free end for instance with a 95 friction roller 61, located in coöperative relation to a disk 62 secured upon the rod 38 and provided upon its periphery with notches 63 and 64. It will of course be understood that the illustration represents 100 only a diagrammatic example and that the details may be such as to meet any desired requirements and further that the specifically indicated parts may be replaced by equivalent elements without in any way 105 affecting the operation and efficiency of my improvement. By way of example it may be mentioned that the cranks specifically shown and described may be replaced by eccentrics, cams or other equivalent devices 110 whereby the intended operation of the parts is secured.

In practice the links 30 and 32 must be of substantially the same length, while the parts of my improved construction are so 115 arranged with respect to each other that the pivotal point 33 may be adjusted with respect to the axial center line of the valve 17 and cylinder 14.

The operation of my invention, referring 120 especially to Figs. 1 to 4 inclusive, is as follows:

Assuming the engine to be at rest with the pointer 40 at "stop" (42^b) and it is desired to start the engine in a direction which 125 for convenience I will designate as "ahead" the crank 39 in the illustrated example is moved upwardly and to the right in the arc of a circle until it engages the stop 43 and its pointer 40 registers with the designation 130

42 on the plate 41. As the crank 39 is thus operated the rod 38 will be rocked in its bearings and thus bring about a rotative movement of the pinion 37 which in turn 5 will actuate the segment 35 upon the pivot 36 and thus swing the arm 34 to the right in Figs. 1 and 2. In this manner the pivot 33 is moved out of registry with the axial center line of the valve 17 and its cylinder 10 and also to the right and the valve 17 is actuated to open communication between the pipes 12 and 16 through the cylinder 14 and its annular chamber 13 whereby compressed air is admitted to the combustion 15 chamber 5^a and thus drives the piston 6 downwardly. This brings about an actuation of the crank 8 and main shaft 9 and also, through the medium of the gears 51 and 50, the auxiliary shaft 49 and the bevel 20 gears 48 and 47, causes the counter shaft 46 to be rotated. Through the medium of the crank 45 and link 44 this actuation of the counter shaft 46 causes the link 32 to oscillate on the pivot 33 and thus by means of 25 the link 30 and stem 28 operates the valve 17 in such a manner that the compressed air is cut off from the combustion chamber 5^a at the proper instant so as not to interfere with the upward movement of the piston 6 under momentum. As the counter shaft 30 30 continues to operate in the manner described the link 32 will continue to be oscillated on the pivot 33 whereby the valve 17 will be reciprocated in the cylinder 13 to 35 periodically admit compressed air to the combustion chamber 5^a and to cut it off therefrom at the proper instant to cause the engine to continue to operate in the direction it started or in other words "ahead." 40 As the rod 38 is rocked through the actuation of the crank 39 as described the cam 54 will also be actuated and will exert a pressure upon the stem 53 toward the left whereby the valve 52 will be opened against the 45 tension of the spring 52^a and will thus open the communication between the combustion chamber 5^a and the pipe 12. The cam 54 which positively controls said valve 52 is thus coincidentally operated with the other 50 parts of the controlling mechanism so that said valve 52 does not interfere with the communication between the combustion chamber and the source of compressed air when such communication is required in the 55 operation of the engine. During the operation of the engine on air "ahead" the roller 61 of the valve stem 60 will be located in the notch 63 of the disk 62 which is actuated coincidentally with the rod 38 so 60 that the valve 59 in the by-pass 58 will be open, with the result that the pump 56 which is operated by the eccentric 57 when the engine is in motion will simply pump the oil through the by-pass circuit and back 65 to the pipe 55. In consequence of this opera-

tion no oil or other fuel is delivered to the combustion chamber 5^a as long as the parts are in the positions described.

As soon as the engine is running smoothly or has reached a predetermined momentum 70 the crank 39 is moved back from the position in which its pointer 40 registers with the designation 42 until said pointer registers with the designation 42^a on the plate 41. This will rotate the rod 38, pinion 37 and 75 segment 35 in the reverse direction and will swing the arm 34 toward the left and so as to bring the pivot 33 into substantial registry with the axial center line of the valve 17 and cylinder 14. With the parts in this position the links 30 and 32 are simply oscillated or swung back and forth on the pivots 29 and 33 as the crank 45 and counter shaft 46 are actuated, without having an appreciable effect upon the valve 17. The operation of the parts is due to the fact that the pivots 29 and 33 are in approximate registry with each other. At the same time the described reverse rotation of the rod 38 has moved the cam 54 to a position in which it 80 releases the valve 52 which accordingly closes under the action of the spring 52^a and under the force exerted by the air which is compressed in the cylinder 5 by the piston 6. The force exerted by the explosions of 85 the fuel in the combustion chamber 5^a also tend to force the valve 52 into firm engagement with its seat as will be readily apparent. In this manner communication between the pipe 12 and the cylinder 14 is cut off 90 regardless of whether or not the pipes 12 and 14 are in communication with each other. The operation of the rod 38 will also bring about a rotation of the disk 62 and will cause the roller 61 to pass out of the notch 63 95 whereby a downward pressure will be exerted upon the stem 60 and the valve 59 will be closed. As the oil or other fuel can now no longer pass through the by-pass 58 it will be injected into the combustion chamber 5^a 100 by the pump 56 and there converted into an explosive mixture and ignited in the usual manner. The engine at this stage is therefore being operated on oil, the direction of 105 operation being "ahead" or in the same direction as when started; in other words the engine may be said to be in ordinary operation. 110

If, while the engine is running ahead occasion should arise making it necessary or 115 desirable to reverse the engine, the crank 39 is moved from the designation 42^a to the left in the arc of a circle until it again engages the stop 43 and its pointer 40 registers with the designation 42^d on the plate 41. This 120 operation again rotates the rod 38 and with it the disk 62, the movement being almost a complete revolution of the parts mentioned, so that the roller 61 again drops into the notch 63 whereby the valve 59 is again 125 130

opened. The oil or other fuel will thus again be pumped through the by-pass 58 by the pump 56 and will no longer be injected into the combustion chamber 5^a of the cylinder 5. 5 At the same time through the medium of the rod 38, pinion 37 and segment 35 the arm 34 will be swung downwardly from its previous position whereby the pivot 33 and links 32 and 30 are similarly moved and the valve 17 10 is drawn downwardly in its cylinder 14. In this manner communication between the pipes 12 and 16 is again established but this time in a different relation from that previously mentioned. In other words with the 15 crank 39 set at the point 42 the lower end of the valve 17 controls this communication, the compressed air passing through the channel or channels 20, while with the crank 39 set at the point 42^a the upper end of said 20 valve represents the effective controlling medium. At the same time the actuation of the cam 54 as the rod 38 is rotated as described will again open the valve 52 so that the combustion chamber 5^a is in free communication 25 with the pipe 12. The operation of the valve 17 with the parts in this position is such that the initial blast of compressed air will be admitted into the cylinder 5 at the proper instant to bring about a reversal of the 30 direction of movement of the engine. Through the medium of the crank 45 and link 44 the link 32 will, at this stage, be also oscillated and thus by means of the link 30 cause the valve 17 to be reciprocated in the cylinder 35 14 in the same way as before. The compressed air is thus again supplied to and cut off from the combustion chamber 5^a at the proper instant to maintain the reverse direction in the engine in the same way as described with respect to the forward movement 40 of the engine. As soon as the latter is running smoothly or has reached the required momentum upon reverse, the crank 39 is moved back until its pointer 40 registers 45 with the designation 42^c on the plate 41. This causes the rod 38 to be again actuated and operates the disk 62 to close the valve 59 and the cam 54 to close the valve 52 and at the same time rotates the pinion 37 and 50 segment 35 to move the arm 34 in a reverse direction until the pivot 33 is again in substantial registry with the axial center line of the valve 17 and cylinder 14. At the same time the cam 54 is again actuated to 55 release the valve 52 which is accordingly again closed under the influence of the spring 52^a and by the action of the air which is compressed in the cylinder by the piston 6 whereby the supply of compressed air 60 from the pipe 12 is again cut off regardless of whether or not the connection between the pipes 12 and 16 is open. At this stage the links 30 and 32 are again simply oscillated concurrently without producing any 65 appreciable operative effect on the valve 17.

With the parts in the described position oil or other fuel is now again injected into the combustion chamber 5^a by the pump 56 and there again converted into explosive mixtures which replace the compressed air as a 70 motive force and continue to operate the engine in a reverse direction.

If after the engine has been reversed it is desired to again operate the same "ahead" the crank 39 is moved from the designation 75 42^c to the designation 42 which again cuts off the fuel from the combustion chamber and opens up the compressed air connection, the operation of the parts being the same as before. As soon as the engine is again running smoothly ahead on air the crank 39 is returned to the designation 42^a whereupon the compressed air connection will again be closed and fuel supplied to the chamber 5^a the operation of the parts being also the 85 same as previously described.

If the initial operation of the engine is to be in the direction herein indicated as reverse the crank 39 is first moved to the designation 42^a and subsequently back to the 90 designation 42^c whereby the desired operation of the engine will be effected in the manner hereinbefore described.

It is to be understood that the parts may be so arranged that the introduction of the 95 oil or similar fuel into the combustion chamber or chambers of the engine, commences before the compressed air has been finally and completely cut off therefrom, without affecting the efficiency of my improved construction.

If it is desired to stop the engine, either when running ahead or on reverse, the crank 39 is moved until its pointer 40 registers with the designation 42^b on the plate 41. 105 This operation again actuates the rod 38 and disk 62 and moves the notch 64 thereof into registry with the roller 61 so that the valve 59 is again opened and the supply of fuel to the combustion chamber 5^a cut off, 110 thereby stopping the engine. In other words, the oil finds its way back to the pump 56 and thus does not reach the combustion chamber 5^a through the spraying nozzle. At the same time the pinion 37 on 115 the same rod 38 has been actuated so as to move the sector 35 and arm 34 in such a manner that the pivot 33 is located at a point between the upper and lower points at which said pivot 33 registers with the axial 120 center line of the valve 17 and cylinder 14. At this stage the intermediate annular space 19 of the valve 17 is in registry with the annular slot 15 and is thus in communication with the annular chamber 13 and pipe 12 125 leading to the cylinder 5, while the radial passages 26 and slots 25 are in registry with the slots 24 of the tubular rod 22. In addition the cam 54 exerts a pressure upon the rod 53 whereby the valve 52 is maintained 130

in its open position. With the parts in this position any pressure remaining in the cylinder 5 whether caused by the operation of the engine on compressed air or on oil is 5 freely released through the pipe 12, space 19, passage 26, slots 25 and 24 and passes out to the atmosphere through the tubular rod 22 and outlets 23.

From this it will be obvious that when the 10 engine is to be again started, the action of the compressed air which represents the initial motive force, will not be hindered by any resistance due to pressure in the cylinder 5. Furthermore when passing quickly 15 from ahead running of the engine to the astern motion thereof, the same release of pressure takes place, so that the absence of a retarding resistance will insure a positive and quick reversal of the engine.

20 The valve 17 may be so constructed that the flanges 18 thereof will uncover the annular slot 15 and bring it into communication with the annular space 19 while the valve is in motion during either ahead or 25 astern running of the engine under the action of the compressed air. By properly proportioning these flanges 18 the described opening of the slot 15 takes place as the piston 6 is moving upwardly in the cylinder 5; 30 with this arrangement compression by the upwardly moving piston 6 of any air contained in the cylinder is prevented. In other words as the piston rises it forces the air in the cylinder through to the atmosphere 35 in the manner hereinbefore described so that a resistance to the upward movement of the piston is removed. The purpose of the described arrangement is to impart to the engine a sufficient momentum under the 40 action of the operating compressed air before the full reaction due to the compression of air by the piston in the cylinder takes place. It will be obvious that with this arrangement it is possible for a high compression 45 engine to receive sufficient momentum under the action of low compression air; the benefits and advantages are obvious and evident.

It will be apparent that in a multi-cylinder engine the crank 39 may be so connected 50 with each individual starting unit as to act in successive steps or stages. In this way it is possible to have a number of cylinders fully working under air at the time another 55 cylinder is already in ordinary operation under oil. As soon as it is apparent that this particular cylinder is working properly, the other cylinders may be brought into ordinary operation in the same way.

60 By providing the valve 52 and by positively controlling the same, the air valve 17 and its cylinder 14 are efficiently protected from the effects of the explosions in the combustion chamber 5^a and at the same time the 65 full force of said explosions is confined in

said combustion chamber and utilized to operate the piston. The life of the air valve 17 and its cylinder 14 is thus prolonged and the efficiency of the engine is increased to a maximum extent.

70 It will of course be understood that the form shown diagrammatically in the drawings has been selected merely for illustrative and descriptive purposes and that the same is not arbitrary and further that my improved arrangement is equally well adapted for use in connection with engines of more than one cylinder. The arrangement provides most satisfactory and efficient results with engines of more than one cylinder. The construction comprises a minimum of parts, is simple and at the same time serves to positively and efficiently control the engine. It will further be apparent 80 that the air valve 17 always operates in predetermined harmony with the piston 6 and that the timing of said valve 17 with respect to said piston 6 is changed by changing the angular position of the arm 34.

85 The preceding description of the operation of my invention has referred only to its combination with, or application to, a single cylinder engine. Under such conditions it is obvious that the engine can never be started in a given direction at will from a 90 previous state of rest unless the engine piston and crank are in a position such that the valves 17 and 52 can be opened to admit operating air to the engine cylinder so as to act upon the piston to move the crank in the 95 desired direction. If, therefore, piston and crank do not stop in a suitable position the engine must be turned over by hand, "barred" over as the expression goes, so as to bring the piston and crank into proper 100 position before attempting to use my device 105 for starting on air.

When the invention is applied to a three (or greater number) cylinder engine, as shown in Fig. 5, for example, it is always 110 possible to immediately start on air, either ahead or reverse, regardless of where the pistons were when the engine stopped, since the cranks and pistons being 120° apart there will always be one piston upon which 115 the air can act and which will be so actuated with respect to the phase of its piston as to turn the engine in the desired direction.

120 Various changes in the specific form shown and described may be made within the scope of the claims without departing from the spirit of my invention.

I claim:

1. In a controlling device for internal 125 combustion engines operated initially by compressed air and subsequently by fuel, means whereby the compressed air is controlled, means for actuating said controlling means to permit air impulses to enter the 130

engine cylinder, and means adjustable to different stationary positions and providing, in all of said positions, a stationary means whereby the operation of said controlling means and the relation of the air impulses to the engine piston is predetermined.

2. In a controlling device for internal combustion engines operated initially by compressed air and subsequently by a fuel, a slide valve whereby the compressed air is controlled, means for operating said valve to permit air impulses to enter the cylinder and for shifting said valve to change the relation between the air impulses and the piston whereby said engine may be reversed, said means being adjustable to a neutral position in which the valve is substantially inactive, mechanism operatively connected with said means whereby fuel is admitted to said cylinder after the air has been discontinued, and an auxiliary valve operatively connected with the slide valve whereby the passage between the slide valve and the engine cylinder is positively closed when the slide valve is in neutral or inactive position.

3. In a controlling device for internal combustion engines operated initially by compressed air and subsequently by a fuel, a slide valve whereby the compressed air is controlled, a link pivotally connected with said valve, a second link pivotally connected with said first link and of substantially the same length, an arm pivotally connected with said second link and forming a support on which said second link swings, means for actuating said links whereby said valve is operated to permit air impulses to enter the cylinder and means for adjusting the position of said arm whereby the position of said second link is adjusted to shift said valve and its operation to change the relation between the air impulses and the piston whereby the engine may be reversed.

4. The combination of a cylinder, a piston movable therein, a crank shaft operatively connected with said piston, a compressed air connection leading to said cylinder, a fuel connection leading to said cylinder, a counter shaft operatively connected with said crank shaft, an air cylinder in said air connection, a slide valve movable in said cylinder for controlling the air connection, a valve controlling the oil connection, a first link pivotally connected with said air valve, a second link pivotally connected at one end with said first link, an operative connection from said links to said counter shaft, an arm pivotally connected with the other end of said second link, a segment connected to move with said arm, an operating rod, a pinion carried thereby in mesh with said segment, a device on said rod operatively

combined with said oil valve, an engine valve controlling the connection between said air cylinder and the engine cylinder, means on said rod for operating said engine valve, and means for operating said rod to change the position of said second link with respect to the first link whereby the position of said slide valve and its operation is adjusted to change the relation between the air impulses and the piston, the operation of said rod coincidentally operating the oil valve to control the oil connection and actuating said engine valve.

5. In an internal combustion engine of the kind described an air cylinder connected with a source of compressed air, a connection from said air cylinder to the engine cylinder, a slide valve in said air cylinder for controlling the air connection, means for actuating and adjusting said slide valve to change the relation between the air impulses and the engine piston whereby said engine may be reversed, an engine valve controlling the connection between the air cylinder and engine cylinder whereby the air cylinder is protected from the effects of explosions in said engine cylinder, and means for actuating said engine valve and for maintaining it in a stationary open position, said last named means being operatively connected with the means for actuating and adjusting the slide valve.

6. In a controlling device for internal combustion engines operated initially by compressed air and subsequently by fuel, a valve for controlling the compressed air, valve actuating means, valve shifting means, means connecting said valve and said valve shifting means with said valve actuating means at a common point and mechanism for adjusting said valve shifting means to vary the relation of said connecting means to each other whereby the operative relation between said valve and said valve actuating means is changed.

7. In a controlling device for internal combustion engines operated initially by compressed air and subsequently by fuel, a valve for controlling the compressed air, means for actuating said valve to permit air impulses to enter the engine cylinder, an engine valve controlling the connection between said air controlling valve and the engine cylinder and means for changing the zone of operation of said air controlling valve relatively to said actuating mechanism and for coincidentally shifting said engine valve to a stationary open position.

8. In a controlling device for internal combustion engines operated initially by compressed air and subsequently by fuel, a valve for controlling the compressed air, valve actuating means, means connecting said actuating means with said valve whereby the latter is operated to permit air im-

5 pulses to enter the engine cylinder and means for adjusting said connecting means to neutralize its effect upon said valve whereby the latter is rendered substantially inactive and the compressed air connection to the engine cylinder is closed.

9. In a controlling device for internal combustion engines operated initially by compressed air and subsequently by fuel, 10 a valve controlling the compressed air, actuating means, a connection from said valve to said actuating means whereby said valve is operated to permit air impulses to enter the engine cylinder, a supporting member, 15 a connection from said supporting member to said actuating means whereby the operative relation of the latter to said valve and of the air impulses to the engine piston is predetermined and means for adjusting said 20 supporting member to different stationary positions whereby said relation is changed.

10. In a controlling device for internal combustion engines operated initially by compressed air and subsequently by fuel, 25 a valve controlling the compressed air, actuating means, a supporting member, links connected with said valve and with said supporting member and connected at a common point with said actuating mechanism, 30 one of said links oscillating on said member whereby the valve is operated to permit air impulses to enter the engine cylinder, and means for adjusting said supporting member to bring the links into approximate 35 registry with each other whereby the valve is shifted to cut off the supply of compressed air to the engine cylinder and the action of said oscillating link upon said valve is neutralized.

40. 11. In a controlling device for internal combustion engines operated initially by compressed air and subsequently by fuel, a valve cylinder connected with the engine cylinder and with a source of compressed 45 air, a valve slidable in said cylinder and provided with a passage extending lengthwise therethrough and constituting a portion of the compressed air conduit in one position of said valve, means for continuously actuating said valve when the engine is in operation to permit air impulses to enter said engine cylinder and means for shifting said valve in said air cylinder to change the relation between the air impulses and 55 the piston whereby said engine may be reversed.

12. In a controlling device for internal combustion engines operated initially by compressed air and subsequently by fuel,

a valve cylinder connected with the engine 60 cylinder and with a source of compressed air, a valve slidable in said cylinder, means for actuating said valve to permit air impulses to enter said engine cylinder and for shifting said valve in said air cylinder to 65 change the relation between the air impulses and the piston whereby said engine may be reversed, said means being movable to a neutral position in which said valve is substantially inactive, and means whereby pressure 70 in said engine cylinder is relieved through said valve when in its substantially inactive position.

13. In a controlling device for internal combustion engines operated initially by 75 compressed air and subsequently by fuel, a valve cylinder connected with the engine cylinder and with a source of compressed air, a stationary tubular rod in said air cylinder communicating with the exterior 80 thereof and provided with a slot, a valve slidably mounted upon said rod for controlling the compressed air, said valve having a radially extending passage adapted to register with said slot when the valve is in 85 its closed position whereby pressure in the engine cylinder is relieved, and means whereby said valve is actuated to permit air impulses to enter the engine cylinder.

14. In a controlling device for internal 90 combustion engines operated initially by compressed air and subsequently by fuel, an air cylinder connected with a source of compressed air and provided with an annular chamber and an annular slot communicating with said chamber and said cylinder, a connection from said annular chamber to the engine cylinder, a tubular rod depending from the upper end of said air cylinder and provided with a plurality of slots intersected by the plane of the annular slot, said rod communicating with the exterior of said air cylinder, a valve slidably mounted on said rod, means for actuating said valve relatively to said annular slot to admit air 105 impulses to the engine cylinder, and for shifting it to a position in which the air connection to the engine cylinder is closed, said valve being provided with a plurality of radial passages adapted in the closed 110 position of the valve to register with the slots in said rod and with said annular slot whereby pressure in the engine cylinder is relieved.

In testimony whereof, I have hereunto set 115 my hand.

CHARLES A. MULLER.
